DOUBLE DOOR OPERATOR

Elmer H. Bushell, San Bruno, Calif., assignor of
one-half to Zela K. Page, Abilene, Tex.

Application June 2, 1950, Serial No. 165,755

1 Claim. (Cl. 268—62)

1

This invention relates to door operators.

An object of this invention is to provide an operator for a pair of doors whereby both doors will open and close in unison.

Another object of this invention is to provide a door operator which will resiliently hold a pair of doors in either open or closed position, the operator including a dashpot means to cushion the final movement of each door to open or closed position.

A further object of this invention is to provide a door operator of this kind which is so constructed that the mechanism may be concealed in the upper portion of the door frame.

With the above and other objects in view, my invention consists in the arrangement, combination and details of construction disclosed in the drawings and specification, and then more particularly pointed out in the appended claim.

In the drawings:

Figure 1 is a plan view of a door operator constructed according to an embodiment of this invention.

Figure 2 is a front elevation partly broken away of the operator and a pair of doors connected to the operator.

Figure 3 is a fragmentary plan view partly in section of one of the operators.

Figure 4 is a fragmentary vertical section of one of the operators and doors.

Figure 5 is a fragmentary sectional view taken on the line 5—5 of Figure 4.

Figure 6 is a fragmentary sectional view taken on the line 6—6 of Figure 3.

Figure 7 is a fragmentary plan view of the adjustable stop for the operator.

Figure 8 is a fragmentary vertical section of a modified form of lower pivot for a door.

Referring to the drawings, the numeral 10 designates generally a door frame formed of vertical side members 11, a horizontal upper member 12 and a horizontal lower member or sill 13. A pair of doors 14 and 15 are swingably mounted within the frame 10 and are operatively connected together as will be hereinafter described for unitary movement to either opened or closed position.

Each door has mounted on the upper corner thereof adjacent the junction between the side members 11 and the head or top member 12 a right angularly disposed plate 16 having a polygonal housing 17 fixed thereto and countersunk in the upper portion of the door. A non-rotatable polygonal key member 18 is loosely mounted within the housing 17 and has fixed thereto an

2

upwardly projecting shaft 19. The shaft 19 rotatably extends through a bushing or bearing 20 which is fixed to a plate 21, and the latter is fixed by fastening means 22 to the upper side of the head member 12. The bushing 20 includes an annular flange 23 at its upper end which provides a spacing means for holding an arcuate lever 24 in upwardly spaced relation to the plate 21. The upper end of the shaft 19 is formed with a pair of oppositely disposed flat faces 25 which engage in a complementary opening 26 formed in the lever 24, and the shaft 19 is tightly clamped in the lever 24 by means of a clamping jaw 27 which is held in clamping position by means of a bolt or screw 28.

The door 14 has the lever 24 associated therewith and the door 15 has a similar complementary lever 24a associated therewith. The two levers 24 and 24a are of like construction. The two levers are pivotally connected together by an elongated bar or link 29 which is provided at the opposite ends thereof with a bifurcated connecting member 30 pivotally secured by means of a bolt 31 to the lever 24 and similarly secured to the lever 24a which is fulcrumed on base plate 21a. A spring 32 is secured at one end to the lever 24 as indicated at 33 and is secured at the opposite end to an upstanding pin 34 which is fixed to an arm 35 bolted by means of a bolt 36 to the upper side of plate 21. An obtusely disposed arm 37 extends from the arm 35 and is formed with an upstanding lug 38 constituting a stop which is engageable by the link 29 to limit the swinging of the doors to open position so that the doors will not strike the door frame.

Preferably the arm 35 is formed with an elongated opening 39 through which the bolt 36 engages so that the stop member 38 may be adjusted relative to the link 29 in order to provide for limiting the swinging movement of link 29 and the two doors to a completely closed position. It will be understood that the stop member 38 provides a means whereby the doors 14 and 15 may be swung relative to the frame 10 in only one direction.

A spring 40 is connected at one end as at 41 to the lever 24a and is secured to an upstanding pin 42 which is fixed to the base plate 21a. In order to provide a means whereby the doors will be held against slamming against the door stops and against the door frame when swung to an open position, I have provided a pair of dashpot members 43 and 43a which are pivotally secured as at 44 and 44a to the plates 21

and 21a, respectively. Each dashpot includes a piston rod 45 and 45a which is adjustably secured to the link 29 by means of clamps 46 and 46a, respectively, which are pivotally connected to these piston rods. As shown in Figure 5, each dashpot includes a cylinder 47 having a piston 48 slidably therein, and at the inner end of each cylinder 47 there is a head 49 formed with an axial opening 50 coaxial with the cylinder 47, and a lateral bleed passage 51 from the passage 50 communicates with the atmosphere.

A needle valve 51a is threaded into the head 49 and is adapted to restrict the communication between the two passages 50 and 51 so that the air will only be permitted to enter or leave the cylinder gradually. Each door has disposed at the lower hinged side thereof a pivot member 52 which is threaded through a plate 53 having a bushing 54. The plate 53 is countersunk in the lower edge of the door, and the door is formed with a socket 55 within which the pivot member 52 is adapted to extend. A lock nut 56 is threaded onto the pivot member 52 for locking the pivot member in adjusted position. A socket member 57 is secured by fastening means 58 to the sill 13, and the lower round end of the pivot member 52 is rotatably engageable in the socket member 57. As shown in Figure 4 the socket member 57 is disposed on the upper side of the sill or bottom member 13; whereas, in Figure 8 the socket member 57a is disposed in countersunk position within the sill.

In the use and operation of this door operator structure, the right angle plate member 16 with the housing or socket 17 is countersunk in the upper hinged corner of the door. The operator structure is mounted on the upper side of the head 12, and the socket 57 is secured either on the upper side of the sill, as shown in Figure 6 or is countersunk within the sill, as illustrated in Figure 8. The vertical position of the door with respect to the door frame is adjusted by means of the threaded pivot member 52 so that the lower edge of the door will clear the sill for the desired distance. The slidable mounting of the key 18 in the socket or housing 17 will permit the necessary vertical adjustment of the door. The step member 38 is adjusted upon unfastening of the bolt 36 to limit the swinging movement of the doors 14 and 15 to open position. When one of the doors is pulled outwardly to open the doors, the other door will be swung to a similar open position by means of the link 29 connecting the two levers 24 and 24a together. The springs 32 and 40 will resiliently hold the doors in fully

closed position. The passage of the springs over the pivots when the doors are moved to fully open position will reverse the direction of the force exerted thereby and serve to hold the doors in fully open position.

The doors will be held against slamming by means of the dashpot structure 43 and 43a. The length of link 29 will be determined by the door opening so that this device can easily be adapted to various openings. In practice link 29 may be furnished relatively long and can be cut off at the point of installation to fit the door opening. The connecting members 30 can be removed and replaced when the link 29 is cut as to length.

15. What is claimed is:

A door operating mechanism to be used with a pair of swingably mounted doors, means swinging said doors from a closed position to an open position, said means comprising a polygonal socket fixed in the upper outer corner of each door, a vertical shaft for each door journaled in said frame and projecting downwardly into said socket, a polygonal key fixed on the lower end of said shaft and vertically movable in said socket, an adjustable pivot means at the lower outer corner of each door, a lever fixed on the upper end of each shaft, a link pivotally connected between each lever, springs connected between said levers and said frame for holding said levers in either door opening or closing position, and dashpot means connected between said link and said frame for retarding the movement of said link in either direction.

ELMER H. BUSHELL.
